UNITED STATES PATENT OFFICE

GEORGE A. BREEZE, OF DETROIT, MICHIGAN

VAPORIZER FOR INTERNAL-COMBUSTION ENGINES

Application filed June 2, 1921, Serial No. 474,517. Renewed April 19, 1926.

This invention relates to liquid fuel vaporizers for internal combustion engines.

It is the object of the invention to provide means for intercepting such relatively heavy particles or globules of liquid fuel as may be carried or entrained in an explosive mixture, to separate such intercepted particles from the main body of the mixture and to heat said particles to the vaporization point without unduly raising the temperature of the mixture as a whole.

To provide for warming the mixture throughout only to the temperature productive of most efficient engine operation by re-introducing into the mixture the heated gas from the vaporized fuel is a further object of the invention.

In attaining these and various other objects the invention contemplates passing the mixture, as it is carried to the engine, through a vaporizing chamber having a portion offset from the main path of the mixture and suitably heated, as for example, by passing a branch exhaust pipe through said portion, a succession of baffle plates being arranged within said chamber to intercept the mixture and provide lodgment for insufficiently vaporizing fuel, with provision for draining such fuel from said baffles into said heated portion of the chamber, so that such fuel will be transformed to a hot gas or vapor and as such will be redelivered into the flowing mixture, moderately elevating the temperature thereof and assisting to complete vaporization of the whole volume of mixture as it passes to the engine.

A preferred embodiment of the invention is hereinafter described and is illustrated in the accompanying drawings, wherein,

Fig. 1 is a view in side elevation of the cylinder block of an engine equipped with the improved vaporizer.

Fig. 2 is a similar view, somewhat enlarged in scale, sectionally showing the vaporizing chamber.

Fig. 3 is a vertical sectional view of the vaporizer taken upon line 3-3 of Fig. 2.

Fig. 4 is a view of the same in horizontal section on line 4-4 of Fig. 3.

Fig. 5 is a bottom view of a baffle-forming

partition plate which is mounted horizontally within the vaporizing chamber.

In these views the reference character 1 designates the cylinder block of an explosive engine, and 2 and 3 indicate respectively the intake and exhaust manifolds of said engine. The explosive mixture, before being delivered to the intake manifold, is passed through a vaporizing chamber 4 which may be attached to said manifold beneath the same and is preferably integrally connected to said manifold. An intake conduit 5 depends integrally from the chamber 4 to be connected with a carburetor (not shown) and an opening 6 in the top of said chamber is adapted to discharge the vaporized mixture centrally into the intake manifold. The conduit 5, in communicating with the chamber 4 is out of registration with the opening 6, said conduit being located in the illustrated form of the invention at one end of said chamber. The vaporizing chamber is laterally extended at one side to form an offset eddy portion 7 out of the vertical plane of the intake passage 5 and opening 6, as shown in Fig. 4, through which the main current of the explosive mixture does not pass. This portion is heated, the illustrated heating means being a branch exhaust pipe 8 having one end opening into a coupling 9 connecting the exhaust manifold 3 with the main exhaust pipe 10, said end being beveled to intercept and divert a portion of the exhaust gases. Said pipe 8, at its other end opens into a larger thin walled heating pipe 11 extending from end to end of the vaporizing chamber, within the offset portion 7 thereof. To discharge the exhaust gases from the pipe 11 there is extended therein the perforated end portion of a muffler pipe 12 which terminally is so reduced as to afford only a very small inlet 13 supplementing the perforations 14. The relatively enlarged pipe 11 increases the surface to which heat is transferred from the exhaust gases and there is also insured a considerable transfer of heat to the perforated portion of the muffler pipe 12, owing to the intimate contact occurring as the gases are forced to escape through the perforations. By thus insuring a consider-

able withdrawal of heat from the exhaust gases, a muffling effect (or pressure reduction) is exerted upon said gases within the heated portion of the vaporizing chamber.

5 15 is a partition plate, which may be formed of sheet metal and which, in the illustrated embodiment of the invention is substantially horizontal, dividing the vaporizing chamber into upper and lower portions having communication only through a series of slotted openings 16 in said plate, approximately bisected by the common plane of the conduit 5 and opening 6, and occupying a diagonal relation to said plane. These openings are out of registration with the conduit 5, and their width is successively increased proportionally to their distance from said conduit, as may be best seen in Fig. 4.

A baffle plate 17 preferably depends from 20 that edge of each opening which is nearest the inlet of the conduit 5 to the chamber 4, and said baffle plates may be economically formed by deflecting downward the metal struck out of the partition 15 in forming the 25 slot 16. The rear portion of the partition 15 is ribbed, as indicated at 18, to provide for seating said plate upon the pipe 11 while maintaining said plate spaced slightly above said pipe. At its front edge said partition 30 is flanged, as indicated at 19, to bear upon a glass plate 20 which forms a window in the vaporizing chamber, and permits the effect upon the mixture to be observed. Said plate is held in position by a suitably apertured 35 clamping frame 21 secured to the chamber 4 by bolts 22.

In the operation of the described construction, the gaseous mixture discharging into the vaporizing chamber from the conduit 5 40 impinges first upon the opposed imperforate portion of the partition 15, thence spreading and flowing toward the openings 16. In entering said openings the mixture is distributed across and successively encounters 45 the baffles 17, which, in deflecting said mixture, tend to separate therefrom the heavier particles or globules of unvaporized fuel. Owing to the diagonal relation of said baffles to the flow of the mixture, the latter tends 50 to urge the liquid fuel lodging on said baffles to flow longitudinally thereof toward the heating pipe 11, and such a flow of the intercepted liquid fuel is further induced by inclining the baffles toward said heating pipe. 55 As is shown in Fig. 3, the entire vaporizer is somewhat inclined to the vertical, thus effecting a corresponding inclination of the baffle plate and lower wall of the vaporizing chamber so as to further assist in directing the 60 flow of all of the accumulated liquid fuel toward the heated portion of the vaporizing chamber. By making the area of the opening 16 initially encountered by the mixture so small as to afford a passage to only a small 65 portion of the mixture, and successively in-

creasing the sizes of said openings, an apportionment of the flow to the entire series of openings is assured, under normal operating conditions, and a utility is derived from the entire series of baffle members. The liquid 70 fuel which is separated from the mixture by said baffles and delivered into contact with the heating element 11 is quickly raised in temperature to the vaporizing point, being then returned into the flowing mixture. The 75 heated vapor thus introduced into the mixture is not of sufficient volume to greatly raise the temperature of the mixture as a whole, but does sufficiently warm the mixture to secure the most effective combustion 80 of the same.

It is to be noted that the thin-walled tube 11 provides a considerable surface for the dissipation of heat to the mixture thus providing for a considerable transfer of heat to 85 the mixture without subjecting the wall of the heater to an undesirably high temperature as in "hot spot" constructions. For the most efficient operation of a fuel vaporizer it is highly essential to avoid surfaces so hot 90 as to prohibit a spreading of the fuel upon said surfaces. The rapidity with which the described heater will acquire and dissipate heat permits the heater to rapidly reach its proper working temperature upon the start 95 of the engine with which the vaporizer is associated, and furthermore permits the heater to quickly respond by a suitable rise or fall of temperature to variations in the flow of mixture through the vaporizing 100 chamber.

It is an important feature of the described construction that the heating means employed to effect vaporization of the relatively heavy particles of fuel is so located as to 105 be ineffective to appreciably raise the temperature of the main body of the flowing mixture. It is to be observed also that the partition plate 15 and its integral baffles remain at a comparatively low temperature, 110 being constantly cooled by contact of the incoming mixture.

The increase in the cross sectional area of the heating pipe 11, as compared to the inlet to said pipe is useful in preventing an overheating of the fuel mixture, since this relation retards the admission of exhaust gas to the heater with respect to dissipation of heat therefrom, and thus reduces the temperature at which the heat is transferred to the fuel 115 mixture.

While the main factor in avoiding overheating of the mixture is the location of the heating pipe out of the path of the mixture, it is to be noted that the arrangement of the 120 heater in close proximity to the wall of the projection 7 (see Figure 3) renders negligible the transfer of heat from said portion to the mixture, and is hence an additional safeguard against overheating. Thus while 125 130

the full surface area of the heater is effective to vaporize any liquid fuel, the shielding relation of the wall 7 to said heater greatly reduces the surface area of the heater which is effective upon the flowing mixture.

What I claim is:—

1. In a vaporizer for internal combustion engines, the combination with a vaporizing chamber having an inlet and an outlet for an explosive mixture, of a pipe extending within said chamber substantially parallel to the direction of flow of the mixture through the chamber but out of the main current of said flow, means for delivering exhaust gases from the engine to one end of said pipe, a perforated discharge pipe for said exhaust gases of a diameter less than of the first mentioned pipe, and extending within the latter, and means within said chamber for intercepting the heavier globules of liquid fuel and delivering the same into contact with said first-mentioned pipe.

2. In a vaporizer for internal combustion engines, the combination with a vaporizing chamber having an inlet and an outlet for an explosive mixture, of a partition within said chamber intermediate the inlet and outlet thereof, having an opening for the passage of the mixture, out of registration with the inlet to the chamber, means for heating a portion of the chamber outside of the main path of the mixture, and a baffle member depending from said partition for intercepting the heavier globules of liquid fuel, said baffle having its lower edge downwardly inclining toward said heated portion of the chamber.

3. In a vaporizer for internal combustion engines, the combination with a vaporizing chamber having an inlet and an outlet for an explosive mixture, of a partition within said chamber intermediate the inlet and outlet thereof, having an opening for the passage of the mixture, out of registration with the inlet to the chamber, means for heating a portion of the chamber at one side of the main path of the mixture, and a baffle member depending from said partition for intercepting the heavier globules of liquid fuel, said baffle having its lower edge downwardly inclined toward said heated portion of the chamber and being integrally struck out of said opening in the partition.

4. In a vaporizer for internal combustion engines, the combination with a vaporizing chamber having an inlet and an outlet for an explosive mixture, of a partition within said chamber intermediate the inlet and outlet thereof, having a series of slotted openings forming passages for the mixture, said openings being successively increased in area in the direction of the flow of the mixture, means for heating a portion of said chamber at one side of the main path of the mixture and baffles depending from said partition respectively adjacent to said openings for

intercepting the heavier globules of liquid fuel, said baffles having their lower edges inclined downwardly toward said heated portion of the chamber to direct the intercepted liquid fuel into said portion.

5. In a vaporizer for internal combustion engines, the combination with a vaporizing chamber having an inlet and an outlet for an explosive mixture, of a partition within said chamber intermediate the inlet and outlet thereof, having a series of slotted openings forming passages for the mixture, said openings being successively increased in area in the direction of the flow of the mixture, means for heating a portion of said chamber at one side of the main path of the mixture and baffles depending from said partition for intercepting the heavier globules of liquid fuel, said baffles having their lower edges inclined downwardly toward said heated portion of the chamber to direct the intercepted liquid fuel into said portion, said baffles having the nature of tongues integral with said partition and struck out of said openings of the partition.

6. In a vaporizer for internal combustion engines, the combination with a vaporizing chamber having an inlet and an outlet for the explosive mixture, of a heating element extending within said chamber parallel to the direction of flow of the mixture and at one side of the path of said flow, a partition within said chamber intermediate said inlet and outlet and formed with a series of slots diagonal to the flow of the mixture and successively encountered by the mixture, said slots being increased successively in width in the direction of the flow, baffle members formed by tongues struck out of said openings and depending from the advance edges thereof, said partition being spaced above said heating element and ribbed to seat thereon, said baffle members intercepting the heavier particles of liquid fuel and deflecting the same into contact with said heating element.

7. A fuel mixture vaporizer comprising a vaporizing chamber having an inlet and an outlet for a fuel mixture, and having a portion transversely offset from the path established from said inlet to said outlet, means for heating said offset portion, and a plate having an imperforate portion opposed to said inlet and having a portion formed with a plurality of openings, to which the mixture is diverted by said imperforate portion.

8. In a vaporizer as set forth in claim 7, means extending from said plate for intercepting unvaporized particles carried by the mixture, and delivering such particles to said offset portion.

9. A fuel mixture vaporizer comprising a vaporizing chamber having an inlet and an outlet for a fuel mixture and having a portion transversely offset from the mixture

path established between said inlet and outlet, a heating chamber associated solely with said offset portion of the vaporizing chamber, and having an outer surface within said offset portion, and means for delivering a heating medium to said heating chamber.

10. In a vaporizer for internal combustion engines, a vaporizing chamber having an inlet and an outlet for an explosive mixture, a partition within said chamber intermediate the inlet and outlet thereof, formed with a plurality of openings for passage of the mixture, portions of said partition marginal to said openings being flanged in 15 a direction reverse to the flow through said openings, to intercept fuel particles entrained by the mixture, and means for heating a portion of said chamber lying beneath said partition, whereby said flanges are 20 adapted to deliver intercepted liquid fuel by gravity to said heated portion of the chamber.

11. In a vaporizer for internal combustion engines, a vaporizing chamber having an inlet and an outlet for an explosive mixture, means for heating a portion of the vaporizing chamber, a partition within the vaporizing chamber compelling a flow of the mixture transverse to the inlet, said partition 25 having a plurality of openings for passage of the mixture and having projections adjacent to said openings for intercepting drops of the fuel entrained by the mixture, said partition being at a level above that of 30 the heating means, and thereby arranged to induce a gravity travel of the intercepted drops substantially toward said means.

12. A vaporizer comprising a vaporizing chamber having an inlet and an outlet for 40 a fuel mixture, and having a portion projecting transversely to the path established between said inlet and outlet, and a tubular heating chamber arranged completely within said projecting portion of the vaporizing 45 chamber, a portion of the wall of said projecting portion being curved in a spaced and substantially parallel relation to said heating chamber.

13. A vaporizer comprising a fuel mixture 50 vaporizing chamber, a plate dividing said chamber into an upper and lower compartment and providing for a flow from the lower to the upper compartment, means for delivering a fuel mixture to the lower compartment, the upper compartment having an 55 opening for the discharge of said mixture, and the lower compartment having a portion offset to one side of the path of mixture flow established by said delivery means and discharge opening, and means for heating said 60 offset portion.

14. A vaporizer comprising a vaporizing chamber having an inlet and an outlet for a fuel mixture, means for heating said chamber 65 and a baffle member disposed within said

chamber between said inlet and outlet formed with a plurality of openings for the flow of mixture, and projections carried by said baffle member between said openings upon the inlet side of said baffle member for intercepting unvaporized particles of liquid fuel.

15. A vaporizer comprising a vaporizing chamber having an inlet and an outlet, means for heating said chamber a baffle member arranged in said chamber between said inlet and outlet, formed with a plurality of openings for the passage of a fuel mixture, and members struck out of said openings and projecting substantially transversely to the flow through said chamber to intercept liquid fuel particles entrained by the mixture.

16. A vaporizer comprising a vaporizing chamber having an inlet and an outlet for a fuel mixture, a baffle member arranged with in said chamber establishing a circuitous path between said inlet and outlet, and deflecting the flow of the mixture parallel to said baffle member, heating means elongated in the direction of flow through said chamber, and projections carried by said baffle member extending toward said heating means at an inclination in the direction of flow.

17. A vaporizer comprising a vaporizing chamber having an inlet and an outlet for a fuel mixture, and having a portion offset 95 transversely to the flow from said inlet to said outlet, a heating chamber disposed within said offset portion having a relatively thin wall as compared to that of said vaporizing chamber, and means for delivering a fluid 100 heating medium to said heating chamber.

In testimony whereof I sign this specification.
